DEVICE TO TRAIN A DENTAL PATIENT TO OPEN AND CLOSE HIS LOWER JAW IN HIS TERMINAL HINGE POSITION

Raymond Cohen, Long Beach, N. Y.

Application November 29, 1955, Serial No. 549,723

5 Claims. (Cl. 128—303)

This invention relates to a device for retruding the lower jaw.

It has been found in the field of dentistry that there is an ideal position that the mandible (lower jaw) should assume in relation to the maxilla (upper jaw) when a person's teeth, either natural or false, are occluded. It would, therefore, be advantageous to have a patient's mandible in the proper position when making a registration of this important phase of occlusal reconstruction. Registrations are commonly made by having the patient bite into a piece of heat softened wax. The wax is allowed to harden and is then removed.

The mandible is in its relatively ideal position in the final phase of closure of the teeth when the head of the condyle of the mandible is seated as far as it will go into the glenoid fossa of the temporal bone, by its own muscular power. It is only in this position that the mandible is capable of a pure hinge movement.

By means of the apparatus embodying this invention it is possible to train the patient to open and close in a pure hinge movement. This is done by having the patient wear the device and have him open and close without letting his teeth meet for a period of at least ten minutes. The device is then removed and it is a simple matter to direct the patient to open and close in his terminal hinge position. At this time a wax recording is made of the relative maxilla mandibular position.

It is an object of this invention to provide a highly improved device which shall include spring means to hold a jaw under tension so that continued opening and closing of the jaw would train the patient to open and close in his terminal hinge position.

It is an object then of this invention to provide a highly improved device of the character described including spring means to hold a jaw under tension so that continued opening and closing of the jaw would render the muscles of mastication in a state of fatigue.

Another object of this invention is to provide a device for the purpose described, that may be worn portably, will work independently of external power or furniture, will fit securely to a variety of different sized people, be comfortable and easy to adjust.

Another object of this invention is to provide an improved shoulder mounting means for a device of the kind described.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention,

Fig. 1 is a side elevational view which illustrates a man wearing the device of the invention;

2

Fig. 2 is a partial perspective view of a device embodying the invention;

Fig. 3 is a vertical cross-section down the center of the device;

5 Fig. 4 is a perspective view of the cup shaped chin sling and tension means portion of the device with the sling flattened;

Fig. 5 is a cross-section taken on line 5—5 of Fig. 4; and

10 Fig. 6 is a cross-sectional view taken on the line 6—6 of Fig. 4.

Referring now in detail to the drawing, Fig. 2 shows the device 10 embodying the invention and having a shoulder brace 11 at the base thereof. The brace 11 15 comprises a metal plate 11a having a long flat mid portion 12 adapted to contact the back of the patient, curving up slightly at the ends and formed with a forwardly curving lip 13 at each end adapted for hooking over the shoulder of the patient. Each lip hooks over a shoulder while the broad, flat mid portion 12 rests along the back, as shown in the drawing.

The brace may be made of metal or any other suitable material, and may be provided with a soft inner liner pad 14 of leather or any other resilient material, riveted 25 or otherwise attached to the metal part 11a as at 14a. The leather liner preferably extends beyond the outer edges of the metal piece.

Attached vertically to the brace at the mid portion thereof is an elongated flat bracket 15 secured thereto by rivets 16, or other suitable fastening means. The shoulder brace and vertical bracket may be formed as one piece if desired. The bracket 15 comprises a part 15a which rises at a forward and upward angle rearwardly of the shoulder brace to allow for the curvature of the back, and a vertical portion 15b extending therefrom and located at the back of the head, as shown in Figs. 1 and 3. The vertical bracket extends only to a point about ear-level.

A second vertical bracket 17 of T shape has a central leg 17a which is attached for vertical adjustment to portion 15b or bar or bracket 15 by having a slot 18 formed therein engaged by a bolt 19 passing through an opening in said portion 15b and wing nut 19a secured to the bolt. A rivet 20 fixed to portion 15b and entering slot 18 holds the bracket 17 against rotation of the bolt 19.

Attached to the upper end of leg 17 as by rivets 26, is the center of a curved head engaging member 21 having wings 21a, 21b and forming the top of the T-shaped bracket 17. Padding 23 may be applied to the front face of head engaging member 21. A strap 24 is affixed to one wing 21b of the T-shaped head bracket, and a buckle 25 is affixed to the other wing 21a. Their use will be hereinafter described.

Attached by means of said rivets 26 to the rear of the 55 upper end of leg 17a is a flat, elongated bar 27 extending beyond said wings 21a, 21b. Bar 27 may be made of a resilient metal. The ends of the bar 27 are formed with forwardly bent tabs 28 each having a hole 29 therein. A buckle 30 on a strap 31 is riveted to each of the holes 60 29 by means of grommets 32.

A strap 33 is threaded through each buckle 30. The forward ends of the straps 33 are riveted to coil springs 34 by rivets 35. The coil springs 34 are of a length of wire coiled through its body and looped on the ends. The 65 rearward loop 36 of each spring receives the rivet 35 to fasten it to one of the straps 33. The forward loop 37 of each coil spring 34 is extended by a straight length of wire 38, away from the coiled body of the spring. A tubular sleeve 39 formed with a flat portion 40, encases 70 each of the springs 34. The open end of the case 39 extends a short length past the spring to cover part of the strap 33. The flattened end received the loop 37 and straight portion 38 of the spring 34 therewithin.

A chin sling 41 is provided with each end 42 thereof formed with a hole 43 adjacent the flat portions 40 of the spring case 39. A rivet 44 passes through each hole 43, loop 37 and flat end 40 of the spring case which receives said loop, whereby the spring, case and chin sling are fastened together. The purpose of the spring and case will be hereinafter explained.

The chin sling may be made of leather, or any other suitable material. The sling may be made with a front piece 45 of an elongated oval shape. Two separate pieces 46 and 47, each forming half the shape of the front-piece, may be sewn thereto for reinforcing and to aid in shaping the sling to the chin curve. A piece 48 may cover the seam between the piece 46 and the piece 47.

The method of use may now be seen. The device 11 is fitted to the patient by resting the shoulder brace mid-portion 12 against the back, with each forward lip 13 over a shoulder. The head brace assembly is adjusted for height by means of the wing nut 19, 19a in the slot 18. The head brace member 21 rests against the head in a comfortable position. The strap 24 is passed around the forehead and buckled to the buckle assembly 25. This operation secures the device to the head. The chin sling is then strapped to the chin from the bar 27 by the straps 33 provided. Downward or forward motion of the jaw will stretch the springs 34 which connect the chin sling to the straps, thus putting a degree of tension on the jaw determined by the tensile strength of the springs 34. The ends of bar 27 extend beyond the head brace wings 21a, 21b in order to spread the springs away from the face. However, the cases 39 are also provided to protect the patient from being pinched by contractions of the spring.

The device is applied to a patient for about ten to twenty minutes before the dentist records the jaw to jaw relationship. The patient opens and closes his mouth continuously. This exercise sufficiently fatigues the muscles as to render the patient's jaws in a suitably related position for corrective work to be performed by the dentist.

It may be seen that a device has been provided which accomplishes the several objects of this invention, which is safe, comfortable, portable and efficient to a high degree in use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. A shoulder brace having a broad mid-portion contoured to fit the upper portion of a back, a pair of wing portions spreading outwardly and upwardly from said mid-portion, and forwardly curved lip portions extending

from said wing portions adapted to fit a pair of shoulders, an elongated bracket formed with a central portion attached to the mid-portion of said shoulder brace and rising vertically therefrom, a second bracket having an elongated vertical portion adjustably mounted on said first bracket in alignment therewith, a curved head engaging portion formed at the upper end of the second bracket, a strap fastened to one end of said curved portion of said second bracket, an adjustable means for fastening the free end of said strap to the remaining end of said curved portion of said second bracket, and resilient means mounted on the second bracket for gripping a chin, said means for gripping the chin comprising a horizontal bar attached to the rear mid-portion of the said second bracket, said bar having adjustable straps attached at the ends thereof, and a chin sling attached by resilient means to said straps.

2. The combination of claim 1, said resilient means comprised of a pair of coil springs, and a pair of flexible cases covering said coil springs.

3. The combination of claim 1, said chin sling comprising a substantially elongated oval of leather lined with a pair of similarly shaped pieces, each substantially half the said oval and seamed at the center with a small piece covering the seam.

4. A brace for shoulder mounting, formed of a brace to overlie a back and a pair of forwardly curved portions one at each end thereof to hook over a pair of shoulders, a second brace, a bracket supporting said second brace above said first brace, said second brace formed of a broad forwardly curved member adapted to accommodate the rear portion of a head, an adjustable strap attached to the outer forward ends of said curved member, a third brace member mounted to the rear of said second brace, said third brace being of an elongated shape with ends disposed horizontally beyond the second said brace, a pair of strap members attached one to each end of said third brace, a chin engaging means, and a pair of covered springs interconnecting the chin engaging means and said pair of strap members.

5. A device for tiring the jaw muscles of a patient, comprising a shoulder-engaging member, a member adapted to engage the back of a head, said members being adjustably interconnected, a strap attached to the head-engaging member and adapted to encircle the head of a patient, a member fixed to the rear of the head-engaging member and having outwardly extending wings disposed outwardly beyond and rearwardly of the forward ends of the head-engaging member, a chin-engaging device, and resilient means connecting said chin engaging device with said wings.
